UNITED STATES PATENT OFFICE.

JOHN F. IRVINE, OF HOUSTON, TEXAS, ASSIGNOR OF ONE-THIRD TO
WILLIAM F. IRVINE, OF ADA, TEXAS.

DESIGN FOR A LINK FOR CLOTHES-LINES.

SPECIFICATION forming part of Design No. 31,747, dated October 31, 1899.

Application filed September 29, 1899. Serial No. 732,118. Term of patent 14 years.

To all whom it may concern:

Be it known that I, JOHN F. IRVINE, a citizen of the United States, residing at Houston, in the county of Harris and State of Texas, have invented and produced a certain new and original Design for a Link for Clothes-Lines; and I do declare the following to be a full, clear, and exact description of the invention, such as will enable others skilled in the art to which it appertains to make and use the same.

The invention relates to a new and original design for a link for clothes-lines; and it consists of a design of the configuration shown in the accompanying drawings, in which—

Figure 1 is a side elevation, and Fig. 2 is a top plan view.

The leading feature of my design comprises

a longitudinal member 1, the ends of which project outwardly, as shown at 2, thence incline downwardly, as shown at 3, thence formed with an eye, as shown at 4, thence extend upwardly parallel with the portion 3, thence diagonally, as shown at 5, and thence around the portion 1.

What I claim is—

The design for a link for clothes-lines, as herein shown and described.

In testimony whereof I have hereunto set my hand in presence of two subscribing witnesses.

JOHN F. IRVINE.
